RIEKEN, OF EINDHOVEN, NETHERLANDS, A LIMITED LIABILITY COMPANY OF THE
NETHERLANDS

DEVICE FOR REGULATING THE TERMINAL VOLTAGE OF GENERATORS

Application filed December 19, 1927, Serial No. 241,212, and in the Netherlands April 12, 1927.

This invention relates to an improvement in or modification of a compounding device for regulating the terminal voltage of a generator. Such a compounding device which 5 permits to effectuate an overcompound regulation or a regulation at a constant terminal voltage, has the disadvantage inherent in the majority of these devices that in the case of the working-circuit being short-circuited the 10 evil is aggravated instead of being remedied. Therefore, with such regulating devices, for example, with the so-called mechanical regulators, it is customary to use, in addition to the regulator proper, a special device which, 15 in the case of short-circuits, serves to limit the short-circuit current.

The invention relates more specifically to a device of the above said class, in which the exciting current of the generator is influenced 20 by means of one or more incandescent cathode discharge tubes connected in parallel with the exciting winding, the heating current of which is regulated in dependency of the main current or of the terminal voltage of the generator by generating in the heating circuit a 25 tension which is dependent of that main current or of that terminal voltage of the generator and which amplifies or weakens a second tension generated in the same circuit substantially independently of the main current or of the terminal voltage.

According to the present invention both above-mentioned tensions are so adjusted relatively to each other that in case the generator 35 is loaded the plate current of the discharge tubes falls off to zero and increases again when the load further increases.

The invention will be more clearly understood by referring to the accompanying drawing which represents, by way of example, an embodiment of the invention, said drawing being a circuit diagram of the elements involved in the invention.

Referring to the figure, 1 denotes the armature of the generator to be regulated, 2 is the exciting winding which may be connected across a current-limiting resistance 6 to a suitable source of tension. In parallel to the said exciting winding is connected a so-called 50 diode 3 the anode and the cathode of which

are indicated by 4 and 5 respectively, a resistance 8 being included in the load current circuit. The heating circuit of the tube 3 comprises a source of tension 7, which in the drawing is a direct current battery. The load current flows through the resistance 8. The voltage drop e produced in the said resistance will rise with an increasing load-current. If the regulation according to the invention had not been provided, the terminal voltage would 60 decrease with an increasing load-current.

Let the tension e be opposed to the tension E generated by the battery 7. When the tension e increases, the heating current of the diode will decrease, as a result of which the 65 internal resistance of the diode becomes larger owing to which the exciting current flowing through the winding 2 increases. Due to this increase the terminal voltage of the generator rises to such an extent that with 70 a regulation at a constant terminal voltage the initial decrease is neutralized thereby. Consequently, from no-load to full-load a substantially constant terminal voltage of the generator will be obtained in that case.

In the case of overloading, the device is so adjusted that the tension e is substantially equal and contrary to the tension E , the latter being consequently neutralized. As a result, the filament 5 will emit no longer and the internal resistance of the tube 3 becomes so 75 large that no current can flow through the diode. If overloading occurs the terminal voltage of the generator will, consequently, have a normal course, in other words: a course 80 as if no compounding device were present.

In the case of a short-circuit, the generator current will increase strongly and a great loss of voltage will occur in the resistance 8. This 85 loss of voltage will predominate over the tension E generated by the battery 7. Therefore, in the heating circuit will flow again a current which causes the diode to function, owing to which the exciting current considerably decreases. Due to the strong increase 90 of the heating current the terminal voltage shows an abnormally abruptly drooping course, the short-circuit current being consequently limited.

What we claim is:

In a device for regulating the terminal voltage of a generator, a discharge tube connected in parallel with the exciting winding of the generator and constituting means for controlling the excitation of the generator, a circuit including means for regulating the supply of heating current to said tube, in consonance with the main current of the generator, said means establishing, in the heating circuit, a tension dependent upon that of the main current, means for generating another tension in the second mentioned circuit substantially independent of the main current, and means whereby both tensions may be varied relative to each other, and whereby, in the event the generator is loaded, the plate current of the discharge tube will be decreased to zero and be increased, again, upon further increase of the load.

In testimony whereof we affix our signatures, at the city of Eindhoven, this 26th day of November, 1927.

NICOLAAS ANTHONY JOHANNES VOORHOEVE.

JOHAN CHRISTIAAN de HAAS.
